(57) **CLAIM**

The ornamental design for a pocket torch, as shown and described.

DESCRIPTION

FIG. 1 is a perspective view of a pocket torch showing my new design;

FIG. 2 is another perspective view thereof;

FIG. 3 is a side view thereof;

FIG. 4 is a top view thereof;

FIG. 5 is a side view thereof;

FIG. 6 is a side view thereof;

FIG. 7 is a side view thereof; and

FIG. 8 is a bottom view thereof.

FIG. 9 is a perspective view of a second embodiment thereof;

FIG. 10 is another perspective view thereof;

FIG. 11 is a side elevational view thereof;

FIG. 12 is a side elevational view thereof;

FIG. 13 is a side elevational view thereof;

FIG. 14 is a side elevational view thereof;

FIG. 15 is a top plan view thereof; and,

FIG. 16 is a bottom plan view thereof.

The broken line showing of the light portion is included for the purpose of illustrating only and forms no part of the claimed design.
